Attorney

UNITED STATES PATENT OFFICE.

HENRY A. SASS, OF NEW YORK, N. Y., ASSIGNOR TO THE ULLMAN MANUFACTURING COMPANY, OF NEW YORK, N. Y., A CORPORATION OF WEST VIRGINIA.

PICTURE-FRAME.

1,232,095.

Specification of Letters Patent.

Patented July 3, 1917.

Application filed June 7, 1916. Serial No. 102,208.

To all whom it may concern:

Be it known that I, HENRY A. SASS, a citizen of the United States, residing at New York, in the county of New York and State of New York, have invented certain new and useful Improvements in Picture-Frames, of which the following is a specification.

This invention relates to certain new and useful improvements in picture frames and it pertains more particularly to the construction of the back.

I provide a new means or manner of securing the glass in the frame so that it will not drop out in taking out and putting in the picture which is to be framed.

I also provide a novel construction of pivoted clasps for holding in place the hinged back which is provided with a hinged support to form an easel. These clasps are made of flexible metal, and can, therefore, be adjusted and are pivotally mounted on the wood underneath the cardboard back and are designed to engage with the latter so as to hold the same snugly against the wood frame.

Other objects and advantages of the invention will hereinafter appear and the novel features thereof will be particularly pointed out in the appended claims.

The invention is clearly illustrated in the accompanying drawings, which, with the numerals of reference marked thereon, form a part of this specification, and in which—

Figure 1 is a substantially central vertical section from front to rear, as on the line 1—1 of Fig. 2, through a frame embodying my present improvement.

Fig. 2 is a rear view of the frame with portions broken away.

Fig. 3 is an enlarged vertical section on the line 3—3 of Fig. 2, looking in the direction of the arrows.

Fig. 4 is an enlarged section on the line 4—4 of Fig. 2, looking in the direction of the arrows.

Fig. 5 is a perspective detail of a portion of the wooden frame showing one of the pivoted clasps thereon.

Like numerals of reference indicate like parts throughout the different views.

Referring to the drawings,

1 designates a picture frame of wood or any other suitable material which may be ornamental in appearance as may be de-

sired and of any preferred shape, these matters not entering into the subject matter of my present invention.

To the back of the frame 1 and hinged thereto, as at 2, is a back 3 of cardboard or any other suitable material, in the present instance being shown as made of a base 4 of cardboard and a covering 5 upon either side thereof, which may be of paper, linen or any other suitable material, or, as is evident, this covering may be omitted. In the present instance the back 3 is hinged to a member 6 of cardboard secured to the back of the wood frame in any suitable manner, the members 2, 3 and 6 being formed of one piece scored at 2' and 3', and in the present instance this member 6 is shown as provided with a ring or the like 7 by which the frame may be hung upon the wall when desired.

For the purpose of supporting a frame on a shelf, table or other support, after the manner of an easel, I provide a supporting member 8 of cardboard or the like which may be covered with paper, fabric or other material similar to the back 3 and this member 8 is hingedly connected to the back 3, as at 9, in any suitable manner, so as to be folded flat against the back 3, as in Fig. 2, or distended at an angle thereto, as seen in Fig. 1, to support the frame after the manner of an easel.

10 is a flexible ligament connecting the pivoted support 8 with the back 3, the said ligament 10 being adapted to be folded between the members 8 and 3 when the former is in its folded condition and when in its distended condition, as seen in Fig. 1, serving to prevent undue movement of the member 8 away from the member 3.

One of the improvements in the construction and make-up of this frame is the special method of construction of the hinged parts of the backs of the frame and of the easel back. Heretofore in the manufacture of articles of this kind, the method used was to cut the cardboard or other material which was intended to be bent backward and forward (namely, to work as a hinge does) into two pieces, and it was necessary to paste the two pieces of cardboard or other material together by the use of a piece of muslin, leather or other flexible material.

This manner of construction, the same being done by hand, required considerable

time to carry out. In addition to this, the result was not as strong and durable and did not have the ornamental appearance which the frame as now produced by me, has. My 5 method of construction is to emboss or score the cardboard or other material in an embossing machine, designed for the purpose. The embossing, or scoring, of this being done by machine, it is done very rapidly 10 compared with the old method, described above, of pasting two pieces of cardboard together, etc.

This method of constructing the hinges is employed in both parts, namely, the back 15 and the separate easel back. The result is also a much stronger, neater and a better frame and back.

Another point of improvement of this 20 method of construction is the fact that in the old method of using two separate pieces of cardboard, it frequently happens that the fibers of the cardboard of the two separate pieces run in different directions; that is to say, the grain of the cardboard does 25 not always run the same, for the reason that the small strips were frequently cut from the long end of a piece of cardboard and the fibers, therefore, of the two separate pieces contracted in different directions, causing 30 a weakness and a tendency to warp on the part of either the one or the other piece of cardboard.

The use of one piece of cardboard serves 35 to strengthen and keep flat the cardboard backs. This method also produces a cleaner and neater and more ornamental frame and is an important feature of the invention.

Inasmuch as there are two separate parts 40 which are hinged, it will be readily seen that considerable time is saved in the construction and manufacture of these hinged parts, as they are embossed in each case on the piece of cardboard instead of using 45 four pieces of cardboard and pasting them together for the back and easel back. The member 8 is constructed, similarly to the back, of one piece, scored at 8' and 8".

In order to hold the back 3 is close relation 50 to the back of the frame 1, I provide flexible or bendable clasps 11, as seen in Figs. 2 and 5. Each clasp has an extension 12 through which passes a pin or the like 13 which secures it to the frame 1 and 55 permits it to move thereon as upon a pivot, so that it may be swung out into the position shown in dotted lines in Fig. 5 and the back 3 placed against the frame 1 and then the clasp 11 is moved on its pivot, so that its 60 engaging member 14 will lie upon the outside of the back, the latter being held between said member 14 and the body portion of the clasp. By this means the clasp is secured to the frame 1 and is covered by the 65 back 3 when the latter is in position, and

the edge portion or bend 15 of the clasp lies substantially flush with the edge of the frame, as seen in Fig. 2. By making the clasps of flexible material instead of stiff metal, as heretofore, the clasp can be bent 70 backward or forward and this ability to bend the flange of the clasp aids to hold the cardboard back more snugly to the frame. In order to permit of movement of the back upon its hinge to remove a picture or to insert one in the frame, all that it is necessary to do is to move the clasps outward upon their pivots until their engaging portions 14 are free of the back, when the latter can be turned up on its hinge. 75

Any suitable number of these clasps may be used upon each side of the frame. Ordinarily, one upon each side near the lower end will be found sufficient, but more may be employed if found necessary. 80

16 is the glass. It is placed in the frame in the usual manner and is there secured by means of paper, fabric or the like which is secured against the glass, as at 17, by paste or any suitable means and thence bent at 90 right angles and secured, as at 18, to the adjacent face of the rabbet in the frame 1 and then secured, as at 19, along the rear face of said frame 1. The glass is thus held securely in place so that it will not fall out 95 and the paper or fabric does not show in front of the picture 20 against which is the usual backing 21. This passepartout of the glass not only secures the latter against falling out, but makes a neat finish to the 100 frame. The clasps 11 are pivotally secured to the back of the frame through this passepartout material and when the back 3 is in position and secured snugly against the back of the frame 1 by the clasps 11, it provides a very neat, as well as dust-excluding 105 construction of the back of the frame.

Modifications in detail may be resorted to without departing from the spirit of the invention or sacrificing any of its advantages. 110

What is claimed as new is:—

1. A picture frame, a back therefor, and a clasp pivoted to the frame between the back and frame and having a portion adapted to embrace the edge of the back only, the 115 pivot of the clasp being concealed by the back.

2. A picture frame, a back hingedly mounted thereon, and a clasp pivotally mounted on the frame between the back and frame and having a portion embracing the edge of the back only to hold the same snugly against the frame, the pivot of the clasp being concealed by the back. 120

3. A picture frame having a hinged back, 125 a support hinged to said back, and clasps pivotally mounted on the frame between said frame and back and having portions engageable over the edges of the back only to hold the same snugly against the frame, the 130

pivots of the clasps being concealed by the back.

4. A picture frame and a back therefor formed of a single piece of material scored at two adjacent points, said back being disconnected from the frame at both of said points constituting a hinge.

5. A picture frame and a member at the back thereof formed of one single piece of material scored at two different points to constitute a hinge, the same having one end

portion fixed with relation to the other portion, both of said scorings being disconnected from the frame and movable with said member.

In testimony whereof I affix my signature in the presence of two witnesses.
